UNITED STATES PATENT OFFICE.

ALFRED DAY, OF PHILADELPHIA, PENNSYLVANIA.

ROASTER AND COOKER.

No. 902,945.

Specification of Letters Patent.

Patented Nov. 3, 1908.

Application filed May 4, 1908. Serial No. 430,667.

To all whom it may concern:

Be it known that I, ALFRED DAY, a citizen of the United States, residing at Philadelphia, county of Philadelphia, State of Pennsylvania, have invented a new and useful Roaster and Cooker, of which the following is a specification.

My invention relates to a new and useful roaster and cooker and consists of means for 10 rotatably mounting the article to be cooked and for adjusting the position thereof.

It further consists of other novel features of construction, all as will be hereinafter fully set forth.

15 Figure 1 represents a perspective view of a roaster and cooker embodying my invention. Fig. 2 represents a sectional view of a roaster or cooker showing the same adapted for use with a different kind of fuel from that for which it is adapted as shown in Fig. 1. Fig. 3 represents a horizontal sectional view on line $x-x$, Fig. 2. Fig. 4 represents a sectional view of the means for engaging the article to be cooked. Fig. 5 represents a partial sectional view of the 20 means for locking the rotating means.

Similar numerals of reference indicate corresponding parts in the figures.

Referring to the drawings, I have found 30 in practice that in order to properly roast or broil an article that it is necessary to place the same above and to one side of the fuel and to have some means for adjusting the position of the support so that a greater or less amount of heat may be obtained and in the drawings, I have shown a construction which I have found in practice to operate successfully, but it will be evident that various changes may be made in the construction, the arrangement of the parts may be varied and other instrumentalities may be employed which will come within the scope of my invention and I do not therefore desire to be limited in every instance to the 35 exact form as herein shown and described but desire to make such changes therein as may be necessary.

1 designates the casing of my roaster and cooker having side walls and a back and 40 one side being open and the top 2 being provided with suitable openings adapted to receive the covers 3, when it is not desired to make use of the openings, and preferably projecting from the rear or back wall is a pipe 4 for connection with a suitable flue or 45 other passage for carrying off the products

of combustion. 5 designates a damper rotatably mounted in said pipe 4.

6 designates guides which are connected on the outer side of each of the side walls 50 in which are slidably mounted the racks 7.

8 designates a rod mounted in the casing and having the gears 9 and 10 thereon which are so situated as to engage with the teeth of the racks 7 on each side of the body 1, a suitable handle 11 being provided for rotating the rod and the gears in order to move the racks

7 to adjust the position thereof. Adjacent the outer end of each of the racks is a recess or seat 12 which is adapted to receive a pin 70

13 one of which is provided with a point 14 and the opposite end with the hand-wheel 15, said pin also carrying a plate or disk 16 provided at suitable points in its face with the recesses 17. Carried by one of the racks

7 is a stud 18 which passes through the rack and upon the head end thereof presses a spring 19, the opposite end of which is connected with the rack 7 in any suitable manner as by the screw 20 it being understood 80

that the spring 19 forms a resilient bearing for the stud 18 in order to cause the same to enter one of the recesses 17 in the plate 16 as the same is rotated, whereby it will be understood that the pin 13, when rotated, is held 85

in its different positions by the stud 18 engaging with the walls of the recesses 17.

21 designates a collar which is adapted to be passed upon the pin 13 and is provided with a set screw 22 so that the said collar can be moved and adjusted upon the pin and held in its adjusted position by proper manipulation of the said screw 22. Connected with or forming part of the collar 21 is a

90 plate 23 from which projects the prongs 24, a second collar 25 being also adapted to be placed upon the pin 13 after the article to be cooked is placed thereon, said collar also having a set screw 26 for locking the same in its proper position and being provided with a

95 plate 27 having the projecting prong 28 thereon. Suitably connected with the casing 1 is a hood 29 which in the present instance

is pivotally connected by means of the removable pins 30 whereby it will be understood that the said hood can be removed and replaced in position as may be necessary, said

hood in its operative position projecting downwardly with its front edge 31 extending a suitable distance below the rack 7 and the

pin 13 carried thereby. Depending from the

100 front edge of the top 2 of the casing 1 is a

105

110

lip or flange 32 and the hood 29 is provided with a lip or flange 33 which is adapted to abut the lip 32 when the hood is in operative position, as will be understood from Fig. 2.

5 I mount mica or other transparent material 34 in openings suitably provided in the hood through which the article to be cooked can be examined or seen, in order that the same can be rotated as the cooking is accomplished.

10 35 designates a plate which extends across a portion of the front of the casing 1 adjacent the lower portion thereof, providing a space 36 between the lower edge and the bottom of the casing for forming a draft.

15 Suitably mounted and connected with the casing are the grate bars 37 which extend between the plate 35 and the back of the casing, these serving to support coal, coke or

20 charcoal, if this character of fuel is desired. The plate 35 forms a shoulder 38 which serves to support the gas burners 39 which can be placed in and removed from position as desired, said gas burners being connected

25 with a nozzle or connection 40 which passes through one of the side walls and to which a pipe can be connected, leading to a suitable source of gas supply.

41 designates guides which are mounted on 30 the front edges of the opposite sides and which serve to receive and hold a removable plate 42 which closes up a portion of the front opening when the device is used with the coal, coke or charcoal, a suitable handle 35 43 being provided for ease of insertion and removal.

The operation of the device is as follows:—When the fuel is to be used as gas, the arrangement of the parts will be as 40 shown in Fig. 1, the hood 29 is thrown back, assuming the position seen in dotted lines, Fig. 2, and the pin 13 is removed from its seats 12 in the racks 7 and is passed through the article to be cooked which insertion is

45 made easy by reason of the point 14 thereon, the collar 21 meanwhile having been placed on the pin 13. The second collar 25 is then placed on the pin 13 and both collars 21 and 25 are moved to a suitable position

50 therein in order to cause the prongs 24 and 28 respectively to enter from opposite sides into the article to be cooked and the set screws 22 and 26 are tightened whereby the article will be firmly held upon the pin

55 which latter is then returned to its seat upon the racks. The gas has been ignited at a suitable time and the casing will cause the heat to be passed upwardly and will be directed against the article from the side and

60 top, the hood 29 having been meanwhile thrown down into position seen in Figs. 1 and 2. The bar 8 is now rotated in order that the racks can be moved inwardly or outwardly depending upon the position it is 65 desired that the article to be cooked shall

assume with respect to the fire and as one side of the article is cooked by grasping the hand wheel 15, the pin 13 can be rotated since the force necessary will force back the spring 19 and permit the rotation of the 70 parts, until the next recess 17 is reached in the plate 16 when the pin 18 will again enter a recess 17 and lock the parts in position. I have found that turkeys, chickens or beef cooked in this manner are much nicer than 75 when cooked in the ordinary manner since the fire is at one side thereof and any fat juices or other matter which it is not desired to have remain in the article will fall therefrom and can be gathered in a bowl 44, see 80 Fig. 2, placed beneath the article for this purpose.

If it is desired to use the device with other fuel than gas, the burners 39 can be removed and the plate 42 placed in position after 85 which the device is ready for operation.

It will be seen that the device is useful as a cooker or roaster alone or can be directly connected up with a gas range and used entirely with this kind of fuel. By removing 90 the covers 3 the openings from the top are adapted for receptacles containing other articles to be cooked, which can be done at the same time.

It will, of course, be understood that the 95 casing 1 can be provided with a suitable asbestos lining or the casing may be made with two walls of metal between which the asbestos may be inclosed.

Having thus described my invention, what 100 I claim as new and desire to secure by Letters Patent, is:—

1. In a device of the character described, a casing, burners suitably supported therein, horizontally - movable supports on the 105 casing, means for moving the same, and a rotatable pin removably mounted in the outer ends of said supports, means whereby said pin may be rotated above and at one side of the burners, and a lock on said supports for locking the pin in its adjusted positions.

2. In a device of the character described, a casing, burners suitably supported therein; horizontally - movable supports on the 115 casing, means for moving the same, a rotatable pin removably mounted in the outer ends of said supports, means whereby said pin may be rotated above and to one side of the burners, and an automatic lock on said 120 supports for locking the pin in its adjusted positions.

3. In a device of the character described, a casing, burners carried thereby, horizontal racks suitably supported on said casing, a 125 rod having gears thereon meshing with said racks for moving the same, a pin removably and rotatably supported by said racks and automatic means for locking said pin in its adjusted rotated position.

4. In a device of the character described, a casing, burners carried thereby, horizontal racks suitably supported on said casing, a rod having gears thereon meshing with said racks for moving the same, a pin removably and rotatably supported by said racks, a spring actuated stud carried by one of said racks and a plate having recesses in its face carried by said pin into which recesses said stud is adapted to enter in order to hold the pin in its adjusted position. 40
5. In a device of the character described, burners suitably supported, horizontal movable supports carried by said casing, means for moving the same, a removable rotatable pin carried by the outer ends of said supports and adapted to be situated above and at one side of the burners, and collars adjustably mounted on said pin and having prongs for engagement with the article to be cooked and a hood supported by the casing and extended over said pin. 45
6. In a device of the character described, a casing having one side open, guides adjacent the edges of the sides, a plate extending across a portion of the front face and having a shoulder at its upper edge and forming a draft opening between it and the body of the casing, burners supported upon said plate and a removable plate adapted to be seated in said guides above the first-named plate for partly closing the open side of said casing. 50
7. In a device of the character described, a casing, burners suitably supported thereby, openings in the top wall of said casing, a horizontally adjustable support for the article to be cooked carried by said casing, said casing being provided with guides for a removable front plate and a hood pivotally connected with said casing and adapted to be thrown out of or into operative position. 55
8. In a device of the character described, a casing, burners suitably supported thereby, adjustable supports carried by said casing, a rotatable pin carried by said supports, a hood pivoted to said casing, a flange extending downwardly along the front edge of said casing, and a flange on said hood abutting said first named flange when the parts are in operative position. 60
9. In a device of the character described, a casing, burners suitably supported, movable supports carried by said casing, means for moving the same, a rotatable pin carried by said supports, said casing being provided with guides for a removable front plate and a hood pivotally connected with said casing and adapted to be thrown out of or into operative position. 65
10. In a device of the character described, a casing, burners suitably supported therein, a removable front plate on said casing above the burners, a plate extending across a portion of the front of the casing with a draft space beneath the same, said plate supporting the burners, movable supports carried by said casing, a rotatable pin carried by said supports and adapted to be situated above and to one side of the burners and a hood adapted to be situated over said rotatable pin when in operative position. 70
